UNITED STATES PATENT OFFICE.

FRIEDRICH WILLIAM NIEHAUS, OF ST. LOUIS, MISSOURI.

IMPROVEMENT IN PIANO SOUNDING-BOARDS.

Specification forming part of Letters Patent No. **152,159**, dated June 16, 1874; application filed April 20, 1874.

To all whom it may concern:

Be it known that I, F. W. NIEHAUS, of St. Louis, in the county of St. Louis and State of Missouri, have invented certain new and useful Improvements in Sounding-Boards for Pianos; and I do hereby declare that the following is a full, clear, and exact description thereof, reference being had to the accompanying drawings, and to the letters of reference marked thereon, which form part of this specification.

My invention relates to sounding-boards for pianos or other stringed instruments having two or more bridges; and it consists in connecting the bridges by means of an equal number of counter-bridges on the under side of the sounding-board, as will be hereinafter more fully set forth.

In order to enable others skilled in the art to which my invention appertains to make and use the same, I will now proceed to describe its construction and operation, referring to the annexed drawing, in which—

Figure 1 is a plan view of the ordinary plate and sounding-board embodying my invention. Fig. 2 is a longitudinal section of the same through the line *x x*, Fig. 1.

A represents the ordinary plate, to which the sounding-board *B* is connected. *C, D*, and *E* represent three bridges, arranged, substantially as shown, on the upper side of the sound-

ing-board. These bridges are connected by means of corresponding counter-bridges *C', D'*, and *E'* on the under side of the sounding-board. By this means a strong, full, sweet, and harmonious tone is obtained.

In experimenting with sounding-boards, I found that neither two nor three bridges would give that sweet and harmonious tone so desirable in pianos and other similar instruments; but by connecting these bridges by corresponding counter-bridges the desired result was obtained. The tones are all harmonious, not a single harsh or discordant tone being in the piano.

Having thus fully described my invention, what I claim as new, and desire to secure by Letters Patent, is—

In combination with a sound-board provided with two or more string-bridges, brace or counter bridges arranged upon the opposite side of the sound-board, and continuous in extent with said string-bridges, substantially as and for the purpose set forth.

In testimony that I claim the foregoing as my own I affix my signature in presence of two witnesses.

FRIEDRICH WM. NIEHAUS.
